UNITED STATES PATENT OFFICE.

GOMER JONES, OF WASHINGTON, DISTRICT OF COLUMBIA, ASSIGNOR TO THE STANDARD VAPOR FUEL IRON AND STEEL COMPANY OF NEW YORK.

SUPERHEATING-FURNACE.

SPECIFICATION forming part of Letters Patent No. 296,176, dated April 1, 1884.

Application filed February 1, 1884. (No model.)

To all whom it may concern:

Be it known that I, GOMER JONES, a citizen of the United States, residing at Washington, in the District of Columbia, have invented 5 certain new and useful Improvements in Superheating-Furnaces; and I do hereby declare the following to be a full, clear, and exact description of the invention, such as will enable others skilled in the art to which it appertains to make and use the same.

My invention relates to furnaces for superheating steam.

The object of my invention is to improve the construction of the fire-box; and the invention consists of the particular arrangement 15 of arches, which will hereinafter be fully described and claimed, reference being had to the accompanying drawings, in which—

Figure 1 represents a vertical section 20 through the furnace, and Fig. 2 a vertical section through one of the flues at each corner of the furnace; Fig. 3, a top plan view of one of the arches.

A represents the furnace; B, the retort 25 enclosed in a superheater; and C, a superheater, located in the downflue.

The furnace A, which may be of any desired shape, is provided with a mixing-chamber, A', and a combustion-chamber, A''. The 30 mixing-chamber is divided into two parts, a and a''. The part a is provided with a doorway, a², for the admission of air. If desired, the walls of the chamber may be provided with apertures, a³, (shown in dotted lines, 35 Fig. 1,) for the admission of air to all sides of the gas-supplier a⁶, which may be of any common form. The part a'' is properly the mixing-chamber, and consists of arches a', sprung from side to side of the chamber A'.

40 These arches are formed of rows a¹ of fire-brick, separated from each other by retaining-bricks a⁵. The rows in the arch above the lower arch register with the space between the rows in the lower arch, and the rows in the 45 top arch register with the space between the rows in the second arch. In other words, the rows in the several arches are arranged in a staggered manner to one another. The retaining-brick a⁵ in the different arches are also

50 arranged in a staggered manner to each other—that is to say, the bricks shown in dotted lines in the second arch a¹ are on substantially the same line as the space between the

retaining-brick in the lower or upper arch, so that the currents of air and gas will be still 55 further broken by the deflection of the retaining-bricks. The air and gas passing through these arches are thoroughly commingled and burned at the top arch, which forms the bottom of the combustion-chamber. The walls 60 of this chamber are lined with fire-brick, and are of octagonal shape, to bring the corners of the chambers nearer the retort, which is seated in any desired manner in the top of the casing. In each of the corners are short cross 65 flues or ports a⁴, connecting the combustion-chamber A'' with the downflues A³, (one only being shown.) These flues are connected in any desired manner to the flue A⁴, leading to a chimney. In all of these flues is a superheating-drum, A⁵, heated by the waste products 70 of combustion which pass downwardly around them.

I do not claim in this application the construction of the retort, as that is covered by 75 Application No. 117,160, filed January 11, 1884; nor the construction of the superheaters, as they are covered by Application No. 116,456, filed January 4, 1884; but

What I do claim is—

1. The combination of a gas-and-air-mixing chamber and a combustion-chamber, said mixing-chamber having a series of arches each formed of rows of brick, with spaces between each row, and the rows in the upper 85 arch being directly over the spaces between the rows in the lower arch, substantially as described.

2. The combination of a gas-and-air-mixing chamber and a combustion-chamber, said 90 mixing-chamber having a series of arches formed of rows of bricks, one arch being separated from the other by retaining-bricks, and the rows of one arch being directly over the retaining-bricks of the lower arch, and the 95 retaining-bricks of the upper arch arranged in a staggered manner relatively to the retaining-bricks of the arch below, substantially as described.

In testimony whereof I affix my signature 100 in presence of two witnesses.

GOMER JONES.

Witnesses:

HENRY DE ZARALA,
HOWARD M. HOLBROOK.
